UNITED STATES PATENT OFFICE.

DON D. MILES, OF AURORA, ILLINOIS.

MAGAZINE BOLT-GUN.

SPECIFICATION forming part of Letters Patent No. 618,116, dated January 24, 1899.

Application filed June 15, 1895. Serial No. 552,907. (No model.)

To all whom it may concern:

Be it known that I, DON D. MILES, a citizen of the United States, residing at Aurora, in the county of Kane and State of Illinois, have invented certain new-and useful Improvements in Magazine-Rifles, of which the following is a specification.

My invention relates to magazine-guns, and has for its object to provide certain new and useful features, such as are hereinafter described. I have desired particularly to so organize the various elements of the gun as to avoid in the greatest possible degree securing screws, bolts, and the like and so as to make easy work of assembling and disassembling the various parts. I have also desired to present means for the easy and certain extraction and ejection of the shell after the projectile has been discharged. I have also endeavored to produce certain improvements in the magazine-feed, to the end that the cartridges shall be presented in proper relation. I have also given particular attention to the organization of my gun in such manner that the user of the arm will be instantly advised when the magazine is empty and the gun will be retained in proper position for recharging the magazine. These several objects and others I have accomplished by the mechanisms and devices hereinafter described; but of course I am presenting in the drawings only one form of my invention, and I recognize at once that various changes can be made without materially departing from the spirit of my invention, and I do not wish, therefore, to be limited to the specific thing shown.

I will set out the characteristic method of action of the several features and desire to be protected in the use of such means as might be substituted for the means here illustrated to accomplish the same results in substantially the same way.

My invention is illustrated in the accompanying drawings, wherein—

Figure 1 is a side view of the gun with the stock removed. Fig. 2 is a view of the other side of the gun with the stock in position. Fig. 3 is a vertical longitudinal section through the gun, showing the several parts with the stock removed. Fig. 4 is a similar section with some parts removed and show-

ing the magazine empty and the last shell in process of being ejected. Fig. 5 is a side view of the breech-bolt and extractor in the relation which the parts assume when the bolt is ready to be withdrawn. Fig. 6 is a plan view of the same with the bolt-lever shown in cross-section. Fig. 7 is a cross-section on the line 7 7 of Fig. 6, looking in the direction of the arrows. Fig. 8 is a rear end view taken on line 8 8 of Fig. 5 and looking in the direction of the arrows. Fig. 9 is a view on the line 9 9 of Fig. 3, looking in the direction of the arrows and showing certain parts in front and behind such section in dotted lines. Fig. 10 is a similar view with the parts in a different position. Fig. 11 is a detail view of the extractor. Fig. 12 is a plan view of the magazine-feed and bottom plate. Fig. 13 is a plan view of the frame with certain parts, including the breech-bolt, removed. Fig. 14 is a section on line 14 14, Fig. 3, with the magazine full of cartridges and shows the means of preventing the cartridges from being forced out of the magazine when the bolt is drawn back. Fig. 15 is a view of the arms or bars connected with the follower, which separates the cartridges in the magazine, the two arms being separated so as to show the manner in which they are connected together.

Like parts are indicated by the same letter in all the figures.

A is the receiver, which is internally threaded at its forward end to receive the gun-barrel A', which contains the cartridge-chamber A², the cartridges being indicated by A³ A⁴ A⁵. Attached to and preferably continuous with the receiver is the rear portion B, which serves, as hereinafter described, as a support for various parts. The receiver is cut away, as indicated at B', to leave a side slot or opening through which the cartridges can be inserted and the shells ejected. In the lower part of the forward end of the receiver is a recess B², which recess is prolonged around the interior of the receiver until it opens out at the forward end of the aperture B'. On the upper inner side of the receiver there is also a slot B³, through which the extractor can be inserted. The receiver has in addition a rear projection C, which is associated with the trigger-plate C', and these two parts are con-

5 nected together and the stock C² secured upon them by means of the transverse screw-bolt C³. The trigger-plate is provided with the loop C⁴ and the forward end C⁵, which is adapted to be slipped laterally into a recess or aperture in the lower portion of the part B.

C⁶ is a thumb-piece on a locking-plate C⁷, one end of which is adapted to slide under the part C⁵ of the trigger-guard and hold it securely in position upon the part B. The trigger consists of the trigger proper, D, the central pivot portion D', and the upwardly-projecting part D². The trigger-guard is shaped as indicated in Fig. 3, with the central aperture and the slots D³ D⁴ for the admission of the trigger. The stock, as indicated in Fig. 2, covers the trigger laterally, so as to retain it in its position.

20 The magazine is composed of the two end portions B and E, both of which are preferably continuous with the receiver, and the side portions E' E² and the bottom plate E³. The part E is recessed, as indicated, and provided with the aperture E⁴, through which projects 25 the catch E⁵ on the bottom plate. This bottom plate has the two side bearing-posts E⁶ at its front end, which are hollowed out in opposition to a like arc-shaped place on the part E, so as to form a bearing for the pivot-piece F. The pivot-piece F consists of the enlarged portion F' and the smaller portion F², both preferably made continuous with the bar F³, (see Fig. 15,) which bar is perforated 30 at the other end to engage a projecting pin F⁴ on the follower F⁵.

F⁶ is a shorter arm provided with the part F⁷, which is received upon the smaller part F² and which bears against the lower forward portion of the follower, as indicated.

40 F⁸ is a spring which is provided with a pin F⁹ to be received into a corresponding hole in the bottom of the magazine bottom plate and a pin F¹⁰ to be received into a hole in the upwardly-projecting rear portion of the bottom plate. The forward end of the spring F⁸ bears against and upwardly forces the two bars F³ and F⁶, which bars are provided with cam-surfaces at the points where they are engaged by the spring, as indicated, so as to 45 permit the two bars to rise responsive to the action of the spring and thus to carry the follower in such a manner as to make it accommodate itself to the number of cartridges in the magazine and present the uppermost cartridge at the proper position of parallelism with reference to the bolt, receiver, and barrel. This is accomplished by forming the cam-surfaces on the bars F³ and F⁶ at different angles, so that one of the bars will travel 50 faster than the other. The rear end of the bottom piece is provided with an upward projection G, which is provided with a vertical semicircular slot at its rear end to receive the shaft G' on the locking-bar C⁷. This shaft 55 has at its upper end a half-head G², and the part B and the upward projection G are both

60 cut out to furnish room for such half-head. This half-head when in the position indicated in Fig. 3 will of course hold the parts together and the bottom in position, but when 70 turned around to the opposite direction will be freed from the part B and will permit the bottom of the magazine, with its associated parts, to be removed.

J is an upwardly-projecting point or stop 75 on the end of the bar F³, and thus associated with the follower, the office of which will be pointed out in connection with the other parts.

K is the breech-bolt, hollowed out interiorly 80 at K'.

K² is the firing-pin, which passes through the small lock K³ and is provided with the centering-flange K⁴ and the striking-point K⁵. This point is adapted to project through the 85 aperture K⁶ in the forward end of the breech-bolt and thus to strike the head of the cartridge when the parts are in proper position.

The breech-bolt has at its forward end the locking-lug L, which is adapted to be received 90 into the recess B² and thus lock the bolt in position for firing. It also has the lug L', with the forward-projecting portion L², which is adapted to pass over on top of the lug L³ at the forward end of the extractor and thus 95 hold the latter down in rigid relation to the bolt when desired. At the other end of the bolt is the enlarged portion M, from which projects the lever M', preferably provided with the finger-ball M² at its outer end. At 100 the same end of the bolt and on the enlarged portion is formed the cam M³ by cutting out the metal of such enlarged portion at M⁴. This cam is adapted to engage the end M⁵ on the cocking-piece M⁶, so that when the bolt is 105 rotated on its axis this cam will force the cocking-piece back, having reference to Fig. 3, thus compressing the spiral spring M⁷ within the bolt and about the firing-pin K² and between the small lock K³ and the flange K⁴ 110 until the parts are brought into the position indicated in Fig. 3. The parts are locked in this position by means of the sear N, which engages a shoulder on the cocking-piece, as indicated. The cocking-piece is provided 115 with the thumb-piece M⁸, and the cocking-piece and firing-pin are secured together by means of the pivot-pin M⁹, which passes through the cocking-piece and rotates therein, projecting into the channel for the firing-pin. 120 The rotating pin is cut out at one side to receive the firing-pin and permit it to be inserted in such channel, and the firing-pin is cut out at one side, so that when it is brought into proper position the pivot-pin may be rotated 125 so as to lock the firing-pin and cocking-piece together.

The sear is pivoted at N' to the elbow crank-lever N² and is upwardly forced by means of the spiral spring N³, which engages the lower 130 side of the sear and rests upon the upper side of the step N⁴, projecting from the elbow crank-

lever. The sear is pivoted to the elbow crank-lever, as indicated in Fig. 3, its pivotal part being inserted sidewise into the recess in the elbow crank-lever therefor. The elbow crank-lever has a somewhat similar portion N^5 , whereby it is pivoted to the part B. One end of the elbow crank-lever N^6 is interposed between the spiral spring N^7 , which bears against the part B and the part D^2 of the trigger. The spring forces it outwardly and thus tends to keep the parts in the position indicated in Fig. 3. The other end of the elbow crank-lever N^8 bears upon the enlarged portion M of the breech-bolt, along the forward edge of such enlarged portion—as, for example, at a point such as is indicated by N^9 ; but when the gun is in condition to be discharged the bolt is situated so that the opening M^4 is opposed to the end N^8 , and therefore the elbow crank-lever can be moved on its pivot to discharge the gun, though at other times it cannot be moved and the gun cannot be discharged.

In the forward portion of the part B there is a recess in which vertically reciprocates the ejector-pin O, provided with the flange O^2 and surrounded by the spring O^3 , which bears against such flange and a shoulder in the recess and tends to force the ejector-pin upward. On the extreme upper end of the ejector-pin is secured the toe O^4 , which projects through a slot O^5 in the forward end and on the lower side of the breech-bolt K. This toe is adapted to engage the base of the shell O^6 and eject it from the gun, as indicated in dotted lines in Fig. 4. When the parts are in this position and the last cartridge and the last shell have been ejected, the follower F⁵ rises and permits the point J or causes the point J to rise to the position indicated and in the path of the bolt, so as to prevent forward motion of the bolt. Thus the gun cannot be closed or brought into position for firing until the magazine has again been charged and the operator has instant notice of the condition of his gun and the fact that the last cartridge has been discharged.

The slot O^5 is cam-shaped, so that when the point J is out of the road the bolt can be moved forward and the ejector will be forced down into its position of preparation, as shown in Fig. 3.

In the lower portion of the cocking-piece there is a recess P, into which the sear N is received when the gun is not cocked, so as to reduce the friction of the end N^8 of the elbow crank-lever against the enlarged portion M of the breech-bolt during the rotation of such bolt. Furthermore, when the gun has been discharged the sear is permitted to rise into the recess P, so as to enable the spring N^7 to easily turn the elbow crank-lever on its pivot and retract the point N^8 from the recess M⁴ and permit the bolt to be rotated on its axis.

The extractor consists of the spring-bar R, with the hook R', which is adapted to pro-

ject forward through the slot B³ and to catch the forward side of the base of the cartridge as such base lies in the place prepared for it in the forward end of the bolt. This extractor, as above explained, has the lug L³, which is adapted under certain conditions to pass under the projection L² on the lug L' of the breech-bolt, and thus hold the forward end of the extractor rigidly in position to grasp the shell when the projectile has been discharged and draw it slightly backward. The other end of the extractor is provided with the dovetailed portion R², with arc-shaped ends R³ R⁴, and the concentrically-disposed pivot-pin R⁴. These parts are adapted to be received into corresponding recesses in the top of the small lock K³, and thus it is necessary for the extractor to be turned upon the pivot on the extractor-head before the two parts can be disengaged, and when in their normal positions they are firmly attached together.

The extractor is provided with the inwardly-projecting lug or leg R⁵, which engages when the parts are in proper position the forward edge of the bolt-head or enlarged portion of the bolt M, and thus locks the extractor-head to the bolt. This lug R⁵ is permitted to come into this position by the notch R⁶ on the forward end of the enlarged portion of the bolt.

On the enlarged portion M, at the point indicated by S in Figs. 5 and 6, is formed a cam, which cam is opposed to and engages the cam S', (indicated in dotted lines in Fig. 1,) so that when the bolt is rotated it is slightly retracted by the action of these two cams, and this takes place during the time when the extractor is locked down securely by the engagement of the lug L³ with the projecting part L².

The device for locking the bolt and the firing-pin, so as to prevent the discharge of the gun, is indicated particularly in Figs. 5, 6, 7, and 8. On the side of the extractor-head is a projection T, which is bored out to receive the mutilated rod T', which rotates in such projection or sleeve T and is cut off at one side. Secured to and projecting from this rod is the arm T², with the thumb-piece T³. On the arm T² is the projecting portion T⁴. When the arm T² is moved by the manipulation of the thumb-piece, which can only be done when the parts are in the position for firing, then the turning of the mutilated rod will cause it to engage a notch in the enlarged portion of the breech-bolt, which notch is indicated in Fig. 2 by dotted lines at T⁵, so that the bolt cannot be rotated. At the same time and by the same action the projection T⁴ engages a slot or cross-cut T⁶ on the cocking-piece M⁶ and prevents the discharge of the gun.

Two notches W W are provided in the receiver, as indicated in Fig. 13, to permit of the easy introduction of the cartridges or the charger which contains them.

The cartridges when placed in the magazine are not placed in line, but are staggered, as shown in Fig. 14. The top of the opening of the magazine near the bolt is contracted, 5 as shown, the sides near the top end of the cartridge being curved, as shown at Z. When the bolt is in position, the top cartridge is prevented from being ejected from the receiver by means of said bolt. When the bolt 10 is drawn back, the top cartridge is moved up to the position shown in dotted lines in Fig. 14 and engages the curved surfaces Z, said cartridge being held in position by the cartridge below it, which tends to force it against 15 said curved surface on account of the position of said cartridge—that is, on account of the fact that the cartridges are staggered.

The use and operation of my invention are probably sufficiently set out in the foregoing 20 description of parts and the drawings. However, I will proceed to describe somewhat briefly the operation of the various parts.

Referring to the magazine, it will be observed that by the use of the single spring and 25 the two pivoted bars which bear against the follower and are themselves borne against by the end of the spring the follower is forced up, its position conforming to that which is necessary for the proper feeding of the cartridges. This action is further effected by 30 the cam or curved surfaces of the spring and bars at their point of engagement. A lug on one of the bars, and of course it might be on the follower and in any event is associated 35 with the follower, projects up into the line of travel of the bolt when the last cartridge has been used. By this means if the operator tries to push the bolt forward, supposing that there is still a cartridge in the gun, he will find 40 the motion of the bolt intercepted at the start and will know by that at once that the magazine has been completely emptied, and he will obtain this information before the parts have gotten into an abnormal position and before 45 the mouth or opening of the magazine has been closed, so that the instant that he feels the bolt checked in its forward motion he knows that the magazine is empty, and he will immediately proceed to fill it, whereupon 50 and by which action the lug is taken out of the path of the bolt and the gun is free to operate.

In the matter of extracting the shell when the projectile has been discharged the operation 55 is as follows: The hook on the end of the extractor passes into the slot at the forward end and in the upper interior portion of the receiver, and in this position the hook overhangs and tightly grasps the rim of the head 60 of the cartridge. The cartridge having been discharged, it is necessary to extract the shell, and this sometimes requires considerable power. I have therefore provided the means illustrated. The lever M' is moved upwardly, 65 so as to rotate the bolt slightly, and two simultaneous actions ensue. The projection L'

on the lug L' passes above or over the lug L³ on the extractor R, thus securely holding it down against the bolt and causing it to firmly hold the rim of the cartridge or shell; but 70 at the same time and just as soon as the extractor has thus been clamped securely down the cam S on the enlarged portion of the bolt engages the corresponding cam S' on the inner surface of the receiver and moves the bolt 75 slightly backward, thus loosening the cartridge or shell from its discharging-chamber. The further rotation of the lever and bolt to permit the withdrawing of the bolt carries the lug L² beyond the lug L³ and frees 80 the parts, the strength of the extractor R being sufficient from that time forward to hold the shell in position. The extractor is now brought toward the rear, the bolt having been brought into the position indicated in 85 Fig. 5, and with the bolt and extractor comes the shell until the lower edge of its rim engages the toe O⁴, which toe has slipped into the slot O⁵, as indicated in Fig. 4. The sharp upward action of this toe incident to the pressure of the spring O³ tips the shell, as indicated in dotted lines, and throws it out of the gun. At the same time the spring in the bottom of the magazine moves the follower and cartridges up until the next cartridge is about 90 opposite the end of the bolt, whereupon the forward motion of the bolt forces such cartridge into position for firing, as illustrated in Fig. 3.

Referring to Fig. 3, it will be seen that the 100 firing-pin has been withdrawn, so as to compress the spring M⁷ by the action of the cocking-piece, the cocking-piece being held in retracted position by the sear N. Now if it is desired to lock the parts in this position it is 105 accomplished by means of the thumb-piece T³ and pivoted arm T², which when operated will cause the locking of the parts as follows: The mutilated bolt or rod T' within the sleeve T engages the corresponding notch in the enlarged end of the bolt, so as to prevent rotation of the bolt, and at the same time the point or projection T⁴ on the arm T² engages the corresponding slot T⁶ in the cocking-piece and prevents it from being released, so 110 as to permit the spring M⁷ to force the firing-pin and cocking-piece forward. When these parts are moved up into the position indicated in Fig. 8, all the parts are free to act, and if the trigger be pulled the sear will be 115 withdrawn, being forced down by the action of the elbow crank-lever against the action of the spring N⁸, whereupon the firing-pin is forced forward and the cartridge is discharged. This action or discharge can only 120 take place when the parts are in the position indicated in Fig. 1, at which time the notch or recess M⁴ in the enlarged end of the bolt is opposite the end N⁸ of the elbow crank-lever, so that such elbow crank-lever can be 125 moved to move the sear. When the discharge has taken place, the sear rests in the recess 130

On the cocking-piece and the parts will assume the position indicated in Fig. 3, so as to permit the rotation of the bolt. The moment the bolt begins to rotate the end M^5 of the 5 cocking-piece engages the cam-surface M^3 , and the cocking-piece is retracted until when the bolt has reached the limit of its rotation the cocking-piece has been restored to the 10 position indicated in Fig. 3. The bolt is then retracted and the shell discharged. The bolt is then forced forward, bringing the new cartridge into position for firing, and the bolt is then turned so as to bring the parts into the position indicated in Fig 1, where the gun 15 is ready for discharging or where the parts may be locked in position by the manipulation of the thumb-piece T^3 , as above described.

It will be noticed that in putting this gun together no screws or the like are employed, 20 with the exception of the single bolt which holds the stock and gun together. The sides of the magazine are undercut or dovetailed to the end pieces and are held in position by the bottom piece.

25 The method of inserting the trigger and the trigger-guard has been described; also, the method of inserting and pivoting the sear and the elbow crank-lever which controls it; also, the method of pivoting the two bars 30 which control the follower; also, the method of locking the cocking-piece and firing-pin, and also the method of securing the extractor.

I have shown my gun in a concrete form, and the drawings are taken from a success- 35 fully-operative gun; but I have of course contemplated numerous alterations of greater or less importance and have also contemplated the use of a portion of these several devices with other devices. I do not therefore wish 40 to be limited to the particular and precise forms here illustrated or to the complete combinations of all of these features. I wish the drawings and description to be taken as setting forth a particular form of my more 45 general invention.

The cam-surfaces on bars F^3 and F^6 are necessarily at different angles, so that one of the bars will travel faster than the other. This is indicated by the varying position as- 50 sumed by the bars in the drawings.

The cartridges when the bolt is drawn back are forced upwardly by the spring and bars and follower; but they engage the upper walls of the frame of the gun, so as to stop 55 their upward motion.

I claim—

1. In a gun a magazine comprising end portions consisting of downwardly-projecting parts from the gun proper, said portions undercut or dovetailed into the ends, and a bottom portion secured to the ends and holding the sides.

2. In a gun a magazine provided with a bottom which is hinged at one end and a securing fastening at the other end, which fastening engages a fixed portion of the gun when turned in one direction and is free to be lifted

out with the magazine-bottom when turned in the other direction.

3. In a gun a device for securing the magazine-bottom which consists of a pin with a mutilated head and a portion which projects under the bottom, in combination with a channel for such pin formed partly in the bottom portion and partly in the fixed portion of the 75 gun, and a recess for the mutilated head formed in the fixed portion of the gun.

4. In a gun the combination of a removable magazine-bottom, with a removable trigger-guard, and a joint-lock for the same which 80 when in one position locks both and when in the other frees both for removal.

5. In a gun the combination of a removable magazine-bottom with a removable trigger-guard, a swinging or rotating lock which has 85 one portion to engage the lower part of the magazine-bottom and another portion to engage the lower part of the end of the trigger-guard.

6. In a gun the combination of a removable magazine-bottom with a removable trigger-guard, a swinging or rotating lock which has one portion to engage the lower part of the magazine-bottom and another portion to engage the lower part of the end of the trigger-guard, 95 and which is provided with a mutilated head to engage a corresponding recess in the gun portion, so that when in one position the bottom and trigger-guard are securely locked to the gun, while in the other position 100 both are freed from the gun.

7. In a gun-magazine the combination of a follower, upon which the cartridges are supported, two bars of different lengths, one end of each bar engaging said follower at different points, the other end of the bars being jointed to a fixed part and a spring which engages said bars and tends to force them upwardly, substantially as described.

8. In a gun-magazine the combination of a 110 follower with two bars of different lengths which engage the follower at different points and a spring which bears against and so tends to force the two bars upward and cam-surfaces of different inclinations on the bars at 115 the points engaged by the spring and whereby the follower is brought upwardly at the right angle.

9. In a magazine for guns the combination of a downwardly-depending end piece and 120 an upwardly-projecting bottom piece with a pivot-bearing formed between them, and means for lifting the follower pivoted in such pivot-bearing.

10. In a gun-magazine the combination of 125 a follower with a bar which engages one end and is provided at the other with laterally-projecting pivot portions of different diameters, a second bar adapted to engage the follower and provided with a pivot portion to receive the smaller pivot portion of the other bar, and a pivot-bearing to receive the pivot and hold the two bars together.

11. In a gun-magazine the combination of

a follower with a bar which engages one end and is provided at the other with laterally-projecting pivot portions of different diameters, a second bar adapted to engage the follower and provided with a pivot portion to receive the smaller pivot portion of the other bar, and a pivot-bearing to receive the pivot and hold the two bars together, said bearing

formed between the two opposing parts of the end of the magazine.

Chicago, Illinois, June 7, 1895.
